UNITED STATES PATENT OFFICE.

LUCIEN H. HANDY, OF SAN FRANCISCO, AND CHARLES S. HOSFORD, OF BERKELEY, CALIFORNIA, ASSIGNEES TO GOLDEN GATE NOVELTY MANUFACTURING CO., OF SAN FRANCISCO, CALIFORNIA, A CORPORATION OF CALIFORNIA.

DOOR-LOCK AND BURGLAR-ALARM.

SPECIFICATION forming part of Letters Patent No. 718,454, dated January 13, 1903.

Application filed August 8, 1902. Serial No. 118,904. (No model.)

To all whom it may concern:

Be it known that we, LUCIEN H. HANDY, residing in the city and county of San Francisco, and CHARLES S. HOSFORD, residing at 5 Berkeley, county of Alameda, State of California, citizens of the United States, have invented certain new and useful Improvements in Burglar-Alarms and Door-Locks; and we do hereby declare the following to be a full, 10 clear, and exact description of the same.

Our invention relates to the class of devices for locking doors and giving the alarm upon an attempt to open the same.

Our invention consists in the novel combinations, construction, and arrangement of parts, which we shall hereinafter fully describe and claim.

The object of our invention is to provide a simple and effective device of this character.

Referring to the accompanying drawings, Figure 1 is a perspective view of our device as applied to a door, the alarm and lock being set and ready to operate. Fig. 2 is a front view, partly broken, of our device, both 20 bolts being projected in operative or set position. Fig. 3 is a rear view of the device, the back wall of the casing being removed. Fig. 4 is a section on line $x-x$ of Fig. 2. Fig. 5 is a view of the interior front of the casing C, both bolts being removed. Fig. 6 is a detail elevation of the inner surface of the back wall of casing C.

A, in Fig. 1, is a portion of a door, A' is a portion of the door-casing, and B is the knob by which the usual latch is operated. Upon the inside face of the door, in any suitable convenient location relatively to the knob, (here shown in Fig. 1 as just above it,) is the casing C, forming the housing and carrier for 35 the various parts of our device. This casing may be constructed in any suitable manner. A good construction is that here shown, in which the casing is formed at one end with a lip c, Fig. 4, overlapping the door edge, and 40 a removable back plate c', Fig. 6, lying flat against the door-face. Screws c², through the casing and through the lip c, pass into the door and hold the casing in place. Within

the casing and slidably mounted upon the inside face of its front wall is a vertically-dis- 50 posed slide-bar D, Figs. 3, 4, and 5, the upper end of which is provided with an arm d, Figs. 2 and 4, which extends at right angles through a slot or opening c³ in the front wall of the casing. The slide-bar D may be seated to move perpendicularly in any suitable manner; but the construction here shown in Figs. 4 and 5 we consider a good one. It consists of two rivets d', passing through two elongated slots d² in the bar and through 60 the front wall of the casing and into the base-shell E, Fig. 4, of the gong or bell F, whereby the latter is secured to and carried by the casing. The trip-arm d of the slide-bar also extends freely into the shell E in a 65 groove or channel e, cut in its top, Fig. 4. Within and between the shell and gong is seated in usual manner the alarm mechanism, which may consist of any suitable and customary parts. In the present case in order 70 to illustrate a suitable alarm device we show in Fig. 2 a plate G, on the back of which is an actuating-spring g, Fig. 4, wound by an arbor g', upon the forward end of which the bell F is screwed, said bell serving, when 75 screwed home, as the key by the turning of which the spring is wound. On the outer face of plate G is carried the usual gear-train g², the terminal member of which vibrates the escapement-pawl g³, to which the hammer 80 g⁴ is connected by the wire g⁵, Fig. 2.

The extremity of the trip-arm d of the slide-bar D within the casing C projects, as shown in Figs. 2 and 4, into the path of movement of the hammer-wire g⁵, and when said trip-arm is raised and held up it will lift up under the hammer-wire g⁵, and thereby throw and hold the escapement-pawl g³ into engagement with the terminal member of the gear-train, as shown in Fig. 2, thereby locking said train 85 and arresting all movement, so that the bell will not ring; but when the trip-arm d is lowered it will free the hammer-wire g⁵ and will thereby give free movement to the pawl g³, which, vibrating under the impulse of the 90 gear-train derived from spring g, will cause

the hammer to strike the gong and sound the alarm. The normal position of the trip-arm *d* is a depressed one to free the alarm mechanism, and to secure this result a spring may 5 be suitably located to affect the slide-bar *D* or its arm *d* to hold them down. We have here shown in Figs. 2 and 4 for this purpose a spring *g*⁶ on the back of plate *G*, which bears on the trip-arm *d* and holds it down. 10 Now in order to control this trip-arm for the needs of the device we have the following parts: Mounted within the upper portion of the casing *C* and adapted to slide therein horizontally is the setting-bolt *H*, Figs. 2 and 15 3. The rear end *h* of this bolt projects from the casing, enabling it to be readily grasped and manipulated. Its forward end is provided with a bevel-faced latch-head *h'*, Figs. 1 and 3, which is adapted to be projected beyond the casing-lip *c*. A friction-spring *h*², 20 Fig. 5, holds this bolt true in sliding, while a coil-spring *h*³, Figs. 3 and 4, secured to the bolt and to the casing-plate *c'*, holds said bolt normally retracted. A small projection *h*⁴, 25 punched from the face of the bolt, comes in contact with the inner end of the casing and serves to limit its retraction. The upper edge of this setting-bolt *H* is formed at *h*⁵, Fig. 3, with an inclined plane which plays under a projection *d*³, extending from the slide-plate *D*, Fig. 4. The relative position of these parts is such that when the setting-bolt *H* is in its normal or retracted position the inclined plane *h*⁵ of said bolt does not contact with the 30 projection *d*³ of the slide-plate *D*, but lies far enough below it to permit said plate *D* to occupy its normally depressed position; but when the bolt *H* is projected the inclined plane *h*⁵ passes under and in contact with the projection *d*³, and thereby lifts and holds the slide-plate *D* up, Fig. 3.

Within casing *C* is horizontally and slidably mounted the locking-bolt *K*, Fig. 3. The rear end *k* of this bolt projects from the casing, whereby it may be manipulated. Its forward end *k'* is adapted to be projected through the lip *c* of the casing. This bolt is steadied by a retaining-spring *k*², Fig. 6, which lightly engages notches *k*³ in its lower edge to sufficiently define its projected and retracted positions. Its movement is limited by a notch *k*⁴ in its upper edge engaging with its terminal shoulders the end wall of casing *C*, Fig. 45. The upper edge of this locking-bolt *K* is formed with an inclined plane *k*⁵, Fig. 3, which is reversed relatively to the inclined plane of the setting-bolt, and it plays under a second projection *d*⁴ from slide-plate *D*, Fig. 4. The arrangement is such that when the 50 locking-bolt *K* is retracted it bears up under projection *d*⁴ and holds slide-plate *D* up, and when said bolt is projected it frees the slide-plate *D* and allows the latter to move down.

Upon the door-casing *A'* is a keeper-plate 60 *L*, Fig. 1. The projecting edge of this plate is formed with a lip *l*, which is adapted to receive the engagement of the bevel-faced latch-

head *h'* of setting-bolt *H*, and it is also provided with a socket *l'* to receive the end *k'* of the lock-bolt *K*. This socket *l'*, it will be 70 noted, is wider than the thickness of the bolt end *k'*, the difference being sufficient to permit the door *A* to be opened far enough to remove, by this act of opening, the latch-head *h'* from the lip *l* of the keeper-plate *L*. 75

The following description of the operation of our device will assist in a better understanding of the construction and arrangement of the parts we have described, in addition to giving their functions and purposes. 80

Suppose the door is to remain on its simple knob-latch *B*, unaffected by our device. Under this condition both bolts *H* and *K* are retracted, and the door is thus left unlocked. Now, although the alarm mechanism is wound up and normally under tension, it is prevented from operating because, though the setting-bolt *H* has relieved the slide-bar *D* and the spring *g*⁶ is tending to press down the trip-arm *d*, and thus to relieve the alarm mechanism, 85 the lock-bolt *K* being retracted holds up slide-bar *D* and its trip-arm *d*, thereby locking the alarm by holding the escapement-pawl *g*³ and keeping it in engagement with the gear-train *g*². Suppose, now, the device is to be set. The 90 first act is to project the setting-bolt *H* so that its latch-head *h'* will engage the lip *l* of keeper-plate *L*, and said latch-head will under the influence of the spring *h*² positively engage said lip, and the latter will hold the 95 bolt projected against the power of the coil-spring *h*³ to retract it. The next act is to project the lock-bolt *K* so that its end *k'* passes into the socket *l'* of the keeper-plate. The 100 door is now locked. The alarm mechanism is, however, still locked, for, although the bolt *K* by its projection has relieved the slide-bar *D* and its trip-arm *d*, the projected bolt *H*, by its inclined plane *h*⁵ pressing under the projection *d*³ of the slide-bar, still holds up said 105 bar and its trip-arm *d*, thus continuing the lock on the alarm mechanism. The door is now, as stated, locked, and the alarm-lock is set. Finally, suppose a visit from an intruder. He pushes open the door to the extent allowed 110 by the wide socket *l'* in the keeper-plate, in which the bolt end *k'* is seated. This movement of the door (which, however, is still secure against opening) is sufficient to carry the latch-head *h'* of the bolt *H* away from the lip 115 *l* of the keeper-plate *L*. Instantly the spring *h*² will retract bolt *H*, and the slide-bar *D* will now be free of both bolts *H* and *K* and subject only to its own spring *g*⁶, which by pressing down the trip-arm *d* will release the alarm 120 mechanism, and the bell will sound. The alarm of the bell cannot be arrested from without and its noise will be incessant until the occupant of the room stops it by either reTRACTING bolt *K* or projecting bolt *H*, thereby 125 lifting the trip-arm *d* again to lock the alarm. 130

Having thus described our invention, what we claim as new, and desire to secure by Letters Patent, is—

1. In a burglar-alarm and door-lock, the combination of a setting-bolt, having a latch-head on its forward end, a fixed lip on the door-casing over which said latch-head works for holding said bolt projected when the door is closed and releasing it when the door is moved to open it, means for retracting said bolt when released, an alarm mechanism and a locking and tripping means controlled by the setting-bolt, to lock the alarm when the bolt is projected and to release it when the bolt is retracted. 70
2. In a burglar-alarm and door-lock, the combination of a setting-bolt, having a latch-head on its forward end, a fixed lip on the door-casing over which said latch-head works, for holding said bolt projected when the door is closed and releasing it when the door is moved to open it, means for retracting said bolt when released, an alarm mechanism, a trip-arm to lock and to release said alarm mechanism and means actuated by the setting-bolt for controlling the trip-arm to lock the alarm mechanism when the bolt is projected and to release it when the bolt is retracted. 80
3. In a burglar-alarm and door-lock, the combination of a setting-bolt, means engaging the forward end of said bolt, for holding said bolt projected when the door is closed and releasing it when the door is moved to open it, means for retracting said bolt when released, an alarm mechanism, a trip-arm to lock and to release said alarm mechanism, a slide-bar carrying the arm, and having a projection, and an inclined plane on the setting-bolt acting on said projection to move the slide-bar to lock the alarm mechanism when the bolt is projected and to release it when the bolt is retracted. 90
4. In a burglar-alarm and door-lock, the combination of a setting-bolt, a locking-bolt, an alarm mechanism, means actuated by the setting-bolt for locking the alarm mechanism when said bolt is projected and releasing it when the bolt is retracted and means actuated by the locking-bolt for locking the alarm mechanism when said bolt is retracted and for releasing it when the bolt is projected. 100
5. In a burglar-alarm and door-lock, the combination of a setting-bolt, a locking-bolt, an alarm mechanism, a trip-arm adapted to lock and to release said alarm mechanism, a slide-bar carrying said trip-arm and having independent projections, and a relatively opposite inclined plane on each bolt adapted by contact with the projections of the slide-bar to actuate the trip-arm to lock the alarm when the setting-bolt is projected and the locking-bolt retracted and to release the alarm when the positions of the two bolts are reversed. 110
6. In a burglar-alarm and door-lock, the combination of a setting-bolt, means for holding said bolt projected when the door is closed and for releasing it by the movement of the door in opening, means for retracting the bolt when released, an alarm mechanism, a means actuated by the setting-bolt to lock said mechanism when the bolt is projected and to release it when the bolt is retracted, a locking-bolt and means actuated by said locking-bolt to lock the alarm mechanism when said bolt is retracted and to release it when it is projected. 120
7. In a burglar-alarm and door-lock, the combination of a locking-bolt, a keeper-socket therefor sufficiently large to permit an opening movement of the door when the bolt is in said socket, a setting-bolt, an engaging lip therefor to hold said bolt when projected, and adapted by the opening movement of the door to release said bolt, means for retracting said setting-bolt when released from its engaging lip, an alarm mechanism, and means controlled by the setting-bolt to lock the alarm when said bolt is projected, and to release it when the bolt is retracted. 130
8. In a burglar-alarm and door-lock, the combination of a locking-bolt, a keeper-socket therefor sufficiently large to permit an opening movement of the door when the bolt is in said socket, a setting-bolt, an engaging lip therefor to hold said bolt when projected, and adapted by the opening movement of the door to release said bolt, means for retracting said setting-bolt when released from its engaging lip, an alarm mechanism, means controlled by the setting-bolt to lock the alarm when said bolt is projected, and to release it when the bolt is retracted and means actuated by the locking-bolt to lock the alarm mechanism when said bolt is retracted and to release it when it is projected. 140
9. In a burglar-alarm and door-lock, the combination of a setting-bolt, a locking-bolt, a keeper-plate having a lip for engaging and holding the setting-bolt when projected and a socket for engaging the locking-bolt when projected, said socket being large enough to permit the door to have an opening movement sufficient to release the setting-bolt from the engaging lip of the keeper-plate, a spring to retract the setting-bolt when released, an alarm mechanism, means actuated by the setting-bolt for locking the alarm mechanism when said bolt is projected and releasing it when the bolt is retracted, and means actuated by the locking-bolt for locking the alarm mechanism when said bolt is retracted and for releasing it when the bolt is projected. 150
10. In a burglar-alarm and door-lock, the combination of a setting-bolt, a locking-bolt, a keeper-plate having a lip for engaging and holding the setting-bolt when projected and a socket for engaging the locking-bolt when projected, said socket being large enough to permit the door to have an opening movement sufficient to release the setting-bolt from the engaging lip of the keeper-plate, a spring to retract the setting-bolt when released, an alarm mechanism, a trip-arm adapted to lock and to release said alarm mechanism, a slide-bar carrying said trip-arm and having independent

projections, and a relatively opposite-inclined plane on each bolt adapted by contact with the projections of the slide-bar to actuate the trip-arm to lock the alarm when the 5 setting-bolt is projected and the locking-bolt retracted and to release the alarm when the positions of the two bolts are reversed.

In witness whereof we have hereunto set our hands.

LUCIEN H. HANDY.
